UNITED STATES PATENT OFFICE.

CLARENCE C. WILSON, OF BRIDGEPORT, CONNECTICUT, ASSIGNOR TO THE COMPRESSED PAPER BOX CORPORATION, OF BRIDGEPORT, CONNECTICUT, A CORPORATION OF CONNECTICUT.

ARTICLE-DISPLAY BOX.

Application filed May 8, 1923. Serial No. 637,415.

To all whom it may concern:

Be it known that I, CLARENCE C. WILSON,
a citizen of the United States, residing at
394 Fairview Avenue, Bridgeport, county
5 of Fairfield, State of Connecticut, have in-
vented new and useful Article-Display
Boxes, of which the following is a specifica-
tion.

This invention relates to a box used for
10 shipping and displaying articles, and has
for an object to provide a simple and im-
proved box construction which will be
simple, strong, not easily broken, which will
securely hold an article on display so that it
15 may be thoroughly examined without han-
dling, will be neat and attractive in appear-
ance, and which will be easy to assemble in
manufacturing.

With the foregoing and other objects in view, I have devised the construction illustrated in the accompanying drawings, in which—

Fig. 1 is a perspective view of the lower portion of the box showing an article as held for display purposes.

Fig. 2 is a longitudinal section through the complete box closed showing how the articles are placed for shipping purposes.

Fig. 3 is a transverse section substantially on line 3-3 of Fig. 2.

Fig. 4 is a plan view of the flat piece of material employed for forming the article holding device.

Fig. 5 is a transverse view through the holding element prior to applying the cloth covering thereto, the section being substantially on line 5-5 of Fig. 7.

Fig. 6 is a similar section showing the cloth as applied thereto, the section being substantially on line 6-6 of Fig. 8.

Fig. 7 is a plan view of the article holding device prior to the application of the cloth covering, and

Fig. 8 is a similar view showing the device
45 after the covering has been applied.

10. anno etibus etem. dicitur. In anno etibus etem
thi et constat eis in libris et ab aliis huius aetatis
perordines in eis etiamque etiam in eis in eis

the articles for shipping and storing purposes, but also is adapted to so support the articles while on display that they may be thoroughly examined without handling. The box as illustrated is preferably made of cardboard, and comprises a lower or body portion 10 open at the top thereof and a cover portion 11 open at the bottom thereof adapted to receive the body portion in telescopic engagement in the usual manner, as shown in Figs. 2 and 3, the usual strip of cardboard 12 being provided in the cover to limit the amount the body portion will be moved into the same.

Carried by the lower or body portion is the article holding and supporting element. This also is preferably made of cardboard and is developed from a single flat strip, as shown in Fig. 4. A strip 13 of the proper size and shape has punched in its mid-section one or more openings 14 preferably substantially the shape shown in Fig. 4 with curved recesses 15 on the opposite lateral sides of these openings. The forming of these openings leave connecting strips 16 and 17 between the two flaps 18 and 19. The cardboard is scored preferably at the outer ends of these openings, as shown at dotted lines 20, so that the flaps may be easily folded and overlapped in superimposed relation as shown in Figs. 5 and 6. The flaps 18 and 19 are of such a width that when they are in overlapped relation the connecting strips 16 and 17 will be arched above the flaps, as shown in Fig. 5. The upper flap, in the present showing flap 18, is made of such a width that when the strip 13 is folded to the position shown in Fig. 5, the outer free edge 21 will contact the connection between the strips 16 and 17 and the flap 19 and give the proper arched effect to the strips. This feature is very desirable in assembling this article as the workman merely has to fold the flaps in overlapped relation and press the sides together until the edge 21 engages this con-

ment with certain markings, and besides the device may be assembled much more rapidly.

After the base or strip 13 has been folded and secured as shown in Figs. 5 and 7, it is covered with a cloth covering 22 of suitable material, such as velveteen. In covering the base, the material, cut to the proper size and shape, is placed over the folded element, as shown in Fig. 7 with the ends of the velveteen folded under and glued to the underside of the flap 19, as shown at 23 in Fig. 2. The cloth over the body of the element is left sufficiently full to allow it to be tucked under the edges of the arched strips 16 and 17, as shown at 24, in Figs. 1, 2, 6 and 8, this tucking under operation being performed with a suitable instrument. After the cloth has been tucked under these arched strips the sides are then folded under the pasteboard support and glued thereto, as shown at 25. The support for the article is then complete and is inserted in the base or body portion of the box.

In the drawing I have shown two openings in the cardboard strip 13 which provides a box adapted to hold two articles such as salt and pepper shakers 26 and of course the box may be made to accommodate any number, as one or more than two articles, by merely making the strip 13 of the proper size and making the number of openings required for the number of articles for which the box is to be employed. In shipping or storage the article is placed on its side between the arched strips 16 and 17 as shown at Figs. 2 and 3, but when the article is to be placed on display the flange 27 is inserted under the opposed edges of two spaced portions, as shown in Fig. 1, by which it is securely held. The holding effect is increased by the curved recesses 15 engaging the sides of the article. The arched portions act as springs to clamp the article to the base and securely hold it for inspection. As the strips 16 and 17 are in one piece with the base the full length of these strips is available making them more resilient as well as more flexible, allowing for easy insertion and removal of the article and rendering the element less liable to breakage during this operation of inserting and removing the article. The feature of making one of the flaps, in the present instance 18, of the proper length to when in the folded position engage the connection between the strips 16 and 17 and the other flap to provide a stop to properly position the elements, and to give the desired arched effect to the holding strips, makes it very easy for the workman to place the elements in proper position before gluing, and it also gives a uniform product. As the strips 16 and 17 are in one piece with the flaps they are more strongly secured to them

than would be the case if they were separate strips glued to the flaps, and are much less likely to become detached therefrom. This construction also requires fewer operations in assembling. It will be apparent that the device is very simple and may be manufactured at a low cost, besides being neat and attractive in appearance.

Having thus set forth the nature of my invention, what I claim is:

1. In a display box, an article holding element comprising a base, and transverse strips attached adjacent their ends to the base and spaced above the same intermediate their ends, said strips being adapted to engage an article to be displayed between their opposed edges and hold it against the base.

2. In a display box, an article holding element comprising a base, and strips in one piece with the base and arched above the base intermediate their ends to allow insertion of an article flange between the same and the base where it will be held by the strips and the base.

3. In a display box, an article holding element comprising a base, and a plurality of spaced strips in one piece with the base and arched above the base intermediate their ends to allow insertion of an article flange between the same and the base, said strips being also provided with recesses in their opposed edges to engage opposite sides of the article and hold it against the base.

4. In a display box, an article holding element comprising a base, flexible strips attached to the base and arched above the base intermediate their ends to allow insertion of an article flange between the same and the base where it will be held by the strips and the base, and a cloth covering over said strips and base and tucked in under the arched portions.

5. In a display box, an article holding element comprising a base made in one piece provided with one or more elongated openings in its mid-section to provide flaps at the opposite ends of the openings and spaced connecting strips between the flaps, said base piece being folded and secured with the flaps in overlapped relation and the connecting strips arched above the same.

6. In a display box, an article holding element comprising a base made in one piece provided with one or more elongated openings in its mid-section to provide flaps at the opposite ends of the openings and spaced connecting strips between the flaps, said base piece being folded and secured with the flaps in overlapped relation and the connecting strips arched above the same, and a cloth covering over said strips and base and tucked in under the arched portions.

7. In a display box, an article holding element comprising a base made in one piece

provided with one or more elongated openings in its mid-section to provide flaps at the opposite ends of the openings and spaced connecting strips between the flaps, opposed edges of the connecting strips being provided with recesses to engage the sides of an article, said base piece being folded and secured with the flaps in overlapped rela-

tion and the connecting strips arched above the flaps, and a cloth covering over said strips folded under and secured to the bottom of the base and tucked in under the arched portions. ¹⁰

In testimony whereof I affix my signature.

CLARENCE C. WILSON.
